UNITED STATES PATENT OFFICE.

STEPHEN DERRINGER, OF PHILADELPHIA, PENNSYLVANIA, ASSIGNOR TO EMILY K. DIETZ, OF PHILADELPHIA, PENNSYLVANIA, TRADING UNDER THE FIRM-NAME OF DIETZ MACHINE WORKS.

CLENCHING DEVICE.

1,172,955.

Specification of Letters Patent.

Patented Feb. 22, 1916.

Application filed September 28, 1915. Serial No. 53,073.

To all whom it may concern:

Be it known that I, STEPHEN DERRINGER, a citizen of the United States, residing in Philadelphia, Pennsylvania, have invented 5 certain Improvements in Clenching Devices, of which the following is a specification.

One object of my invention is to provide a relatively simple and substantial device for automatically clenching the wire staple 10 for holding together the layers or coils comprising a paper tube; the various parts being so arranged as to permit operation of the device at a high speed.

These objects and other advantageous 15 ends I secure as hereinafter set forth, reference being had to the accompanying drawings in which:

Figure 1 is a side elevation, partly in section, illustrating the preferred form of my 20 invention; Fig. 2 is a plan of the apparatus shown in Fig. 1; Fig. 3 is a transverse section of the winding mandrel with a tube thereon; Fig. 4 is a perspective view of the clenching anvil; and Figs. 5 to 8 inclusive 25 are diagrammatic views illustrating the successive steps in the operation of my device.

It is to be understood that the clenching device comprising this invention is primarily designed for use in connection with a 30 tube making machine which, as it constitutes no part of the present invention, is not illustrated. Such a machine automatically feeds a rectangular sheet of paper, cardboard, or the like to a rotary mandrel 35 1 on which it is wound into the form of a tube α having any desired number of layers or laminations. Thereafter a staple 2 of substantially U-shape form is driven into the tube radially thereof so as to permanently fasten the outer end of the paper roll 40 to the body thereof with a view to preventing it unrolling. For the purpose of clenching the ends of this staple, I mount in a suitable recess of the mandrel a bar 3, which 45 with a block 4 of which it forms a part or to which it is fixed, constitutes an anvil. With this idea in view the outer face of the bar has a centrally formed curved recess 5 and with the block 4 is movable longitudinally of the mandrel, either under the 50 action of a plunger 6 pressed toward it by a spring 7 or by means of a rod 8 threaded into an opening 9 in said block.

Both the spring-pressed plunger and the 55 rod are preferably concentric with the outer

surface of the mandrel and the spring with the plunger is held in place by a plug 10 screwed into the end of the mandrel opposite that entered by the rod 8. For longitudinally moving this rod in the mandrel I 60 mount on one of the rotary elements of the winding machine, in the present instance upon one side of a gear wheel 11, a cam 12 and support a lever 13 on a fulcrum pin 14, so that when a roller 15 at the end of one 65 of the lever arms is acted on by said cam, an adjustable bolt 16 carried by its second arm will cause longitudinal movement of the rod 8. This bolt 16 is threaded through the second arm of the lever 13 and is retained in an adjusted position by a lock 70 nut 17.

The finished tube is removed from the mandrel and the clenching operation is completed by any suitable form of stripping 75 mechanism such as an endless chain 20 and a forked tube engaging member 21 which extends partially around the mandrel in position to be moved longitudinally thereof by said chain.

The anvil 3—4 is normally held by the spring-pressed plunger 6 in such a position that when the staple 2 is driven through the tube α its ends strike the curved sides of the recess 5 in said anvil and are bent toward each other as illustrated in Fig. 5. Thereafter the cam 12 acts upon the lever 13 in such manner as to force the rod 8 into the mandrel 1, thereby moving the anvil in the direction of the arrow Fig. 6 and causing one of the flat end surfaces of the bar 3 to engage one of the ends 2^a of the staple so as to bend it parallel with and immediately adjacent the inner surface of the tube. This inner movement of the bar 8 and consequent sliding movement of the anvil is in opposition to the spring 7 so that as soon as the cam 12 releases the roller 15, said spring through the plunger 6, returns the anvil to its normal position, shown in Fig. 100 7. The forked stripper member 21 is so timed as to come into engagement with one end of the tube α , shortly after this action of the anvil, thereby sliding said tube longitudinally off of the mandrel. In so doing 105 however it forces the second end 2^b of the staple 2 against the second flat surface of the outer edge of the bar 3 and said end turns also parallel and into engagement with the inside surface of the tube α . As a 110

consequence the staple is perfectly clenched when the tube is finally stripped from the mandrel and the latter is in suitable position for the reception of another length of 5 paper.

I claim:—

1. The combination with a tube mandrel, of an anvil movable therein; means for moving the anvil to clamp one prong of a 10 staple in a tube on the mandrel; and means for moving the tube to clamp the second prong of said staple.
2. The combination with a tube mandrel, of an anvil movable therein; and means for 15 successively causing relative longitudinal motion of the tube and anvil to successively clamp the prongs of a staple in opposite directions within the tube.
3. The combination with a tube mandrel, 20 of an anvil slideable therein; mechanism for moving said anvil in one direction longitudinally of the mandrel; and a spring for moving the anvil in the opposite direction.
4. The combination with a tube mandrel, 25 of an anvil slideable therein; mechanism for moving said anvil in one direction; a spring for moving the anvil in the opposite direction; and a device for moving the tube on the mandrel to finish the clamping begun 30 by the anvil.
5. The combination with a tube mandrel,

of an anvil slideable longitudinally thereof and having a clamping recess for the prongs of a staple in the tube on said mandrel; mechanism for reciprocating the 35 anvil to clamp one prong of the staple in the tube on the mandrel; and means for stripping the tube from the mandrel to clamp the other prong of the staple.

6. The combination with a tube mandrel, 40 of a bar longitudinally slideable therein and having a staple receiving recess; a rod extending through the mandrel and arranged to operate on said bar; mechanism for positively moving said rod and bar in one direction; a spring for moving said rod and bar in the opposite direction; and a device for causing relative motion of the mandrel and the tube thereon to complete the clamping 45 operation begun by the bar.

7. The combination with a tube mandrel, 50 of a rod longitudinally movable therein; a recessed bar attached to said rod and slideable in a cavity of the mandrel; a spring-pressed plunger normally holding said bar 55 in a definite position; cam mechanism for periodically moving the bar against the action of the spring-pressed plunger; and means for stripping the tube from the mandrel to complete the staple clamping 60 operation begun by the movement of the bar.

STEPHEN DERRINGER.
